The ornamental design for an electrophoresis comb with wedge-shaped teeth, as shown and described.

(73) Assignee: **LIFE TECHNOLOGIES CORPORATION**, Carlsbad, CA (US)

DESCRIPTION

(**) Term: **15 Years**

FIG. 1 is a front, top and side perspective view of an electrophoresis comb with wedge-shaped teeth, according to an exemplary embodiment;

(21) Appl. No.: **29/626,480**

FIG. 2 is a back, top and side perspective view of the electrophoresis comb with wedge-shaped teeth of FIG. 1; FIG. 3 is a front view of the electrophoresis comb with wedge-shaped teeth of FIG. 1;

(22) Filed: **Nov. 17, 2017**

FIG. 4 is a back view of the electrophoresis comb with wedge-shaped teeth of FIG. 1;

FIG. 6 is a left side view of the electrophoresis comb with wedge-shaped teeth of FIG. 1;

(51) **LOC (12) Cl.** **24-99**

FIG. 7 is a top view of the electrophoresis comb with wedge-shaped teeth of FIG. 1;

(52) **U.S. Cl.**

FIG. 8 is a bottom view of the electrophoresis comb with wedge-shaped teeth of FIG. 1;

USPC **D24/233**

FIG. 9 is a front, top and side perspective view of an electrophoresis comb with wedge-shaped teeth, according to an exemplary embodiment;

FIG. 17 is a front, top and side perspective view of an electrophoresis comb with wedge-shaped teeth, according to an exemplary embodiment;

FIG. 18 is a back, top and side perspective view of the electrophoresis comb with wedge-shaped teeth of FIG. 17; FIG. 19 is a front view of the electrophoresis comb with wedge-shaped teeth of FIG. 17;

FIG. 20 is a back view of the electrophoresis comb with wedge-shaped teeth of FIG. 17;

FIG. 21 is a right side view of the electrophoresis comb with wedge-shaped teeth of FIG. 17;

FIG. 22 is a left side view of the electrophoresis comb with wedge-shaped teeth of FIG. 17;

FIG. 23 is a top view of the electrophoresis comb with wedge-shaped teeth of FIG. 17;

FIG. 24 is a bottom view of the electrophoresis comb with wedge-shaped teeth of FIG. 17;

FIG. 25 is a front, top and side perspective view of an electrophoresis comb with wedge-shaped teeth, according to an exemplary embodiment;

FIG. 26 is a back, top and side perspective view of the electrophoresis comb with wedge-shaped teeth of FIG. 25;

FIG. 27 is a front view of the electrophoresis comb with wedge-shaped teeth of FIG. 25;

FIG. 28 is a back view of the electrophoresis comb with wedge-shaped teeth of FIG. 25;

FIG. 29 is a right side view of the electrophoresis comb with wedge-shaped teeth of FIG. 25;

FIG. 30 is a left side view of the electrophoresis comb with wedge-shaped teeth of FIG. 25;

FIG. 31 is a top view of the electrophoresis comb with wedge-shaped teeth of FIG. 25; and,

FIG. 32 is a bottom view of the electrophoresis comb with wedge-shaped teeth of FIG. 25.

The broken lines shown in the figures are included for the purpose of illustrating portions of the electrophoresis comb with wedge-shaped teeth and form no part of the claimed design.
